UNITED STATES PATENT OFFICE.

JOHN McGARY ALLEN, OF MART, TEXAS.

FOLDING CRATE.

Application filed February 18, 1926, Serial No. 89,189. Renewed May 24, 1928.

This invention relates to improvements in folding crates, having for an object to provide a crate employing a novel arrangement and construction of side and end walls which, with setting up of the device in operative position, will be prevented from having any relative movement such as would tend to allow collapsing of the crate, but which, however, can when desired, be immediately released, and caused to swing to their folded positions, thereby materially reducing the size of the device and thus, enabling the transportation of the same in a compact and space conserving form.

15 It is likewise an equally important object of the invention to provide the crate with stay and brace means whereby the same will be supported in set up or opened position and will have the intermediate portion there-
20 of materially braced to such an extent as to avoid liability of collapsing with the stacking of other objects thereon, such means being capable of immediate movement to collapsed or folded position with the folding
25 of the crate.

It is also an object of the invention to provide the crate with forms of side stays or guards which, with the folding of the same, will serve to permit of the securing of the
30 top and bottom sections in juxtaposed relation, as well as prevent relative lateral movement between such sections and additionally, to prevent interference with adjacent objects.

35 Other objects of the invention will be in part obvious, and in part pointed out hereinafter.

In order that the invention and its mode of operation may be readily understood by
40 persons skilled in the art, I have in the accompanying illustrative drawings, and in the detailed following description based thereon, set out one possible embodiment of the same.

45 In these drawings:—

Figure 1 is a perspective view of the improved foldable crate in complete set up position;

Figure 2 is a similar view wherein the
50 end walls of the crate have been folded inwardly to their inoperative positions, or to positions to permit of the placement of various objects or matter therein;

Figure 3 is a similar view wherein the
55 end and side walls have been moved to their folded or inoperative positions;

Figure 4 is a corresponding view showing the crate in its complete collapsed or folded position; and,

Figure 5 is an enlarged fragmentary detail, partly in section, taken on the line 5—5 of Figure 1.

Having more particular reference to the drawings, in connection with which like characters of reference will designate corresponding parts throughout, the improved foldable crate may be stated to comprise a top and bottom section 1 and 2 respectively, the bottom section being preferably formed of a plurality of closed positioned or juxtaposed planks or boards whereby to give continuity of surface, while, of course, the top 1 is preferably constructed of boards or similar material arranged in a relatively spaced relation. The top and bottom sections 1 and
70 2 are of corresponding size and formation, the bottom section 2 having relatively parallel flanges or side strips 3 secured to the opposite sides thereof, as is shown in the accompanying drawings, while suitable
75 bracing strips 4 may be and preferably are disposed transversely of the boards or planks making up the same and as will be understood, are secured thereto in a suitable manner whereby to lend to the rigidity and stability of the assembled device. A plurality
80 of pairs of transversely disposed rods 5 and 6 are arranged upon the intermediate portions of the bottom and top sections respectively, and have the opposite ends thereof
85 extended slightly beyond the same whereby to permit of the mounting of pivotal stays or brace sections 7 thereon, the said sections having motion limiting shoulders or lips 8 formed upon their opposite ends, while
90 other brace sections 9 are pivoted to these opposite ends adjacent the shoulders 8 and as will be understood, are adapted to have their pivotal movement with respect to the
95 braces 7 limited by such shoulders in one direction. That is to say, with arrangement
100 of the pivotally inter-connected brace sections 7 and 9 in relatively parallel relation, as is shown in the Figures 1 and 3, the shoulders 8 will abut adjacent portions of the braces 9 and thereby, will serve to prevent further pivotal movement of the same in one direction. However, pivotal movement
105 as between the braces 7 and 9 in an opposite direction will be permitted and hence, the "breaking" of these braces, as when the top and bottom sections are to be swung or
110

folded to their inoperative or closed positions, will be permitted. The upper ends of the braces 9, as will be noted, are mounted for pivotal movement upon the opposite and 5 extended ends of the rods 6 carried upon and disposed transversely of the top section 1.

To provide the crate construction with further stay and guide means, metal bars or strips, designated herein by the numeral 10 are supplied, said bars being formed with diagonally disposed opposite portions, the extremities of which are fixedly secured to the opposite ends of the aforesaid rods 6, as indicated at 11. At this point, it is to be 15 noted that the stays 10 are off-set laterally with respect to the pivotally connected sections 7 and 9 of the previously described braces and by consequence, with movement of the top and bottom sections to their folded 20 positions, as indicated in the Figure 4, said sections 7 and 9 will be received adjacent the inner sides of the stays 10, while the lower and free portions of such stays may be arranged in a position adjacent the outer 25 faces of the intermediate portions of the previously described strips 3, as is shown in the Figure 4. Hooks or other suitable devices 12 are preferably carried upon the intermediate portions of each of these stays 30 or guards 10 and are adapted to be engaged in eyelets or other keepers 13 secured to the opposite sides and corresponding intermediate portions of the bottom section 2. Thus, it will be appreciated that with 35 engagement of the hooks 12 in their respective eyelets 13, said top and bottom sections 1 and 2 respectively will be secured against relative movement, either laterally with respect to each other or in directions away from each other. Additionally, these guards 10 will serve to prevent interference with other objects with the folded crate and likewise, will serve to secure proper movement of the hingedly connected sectional braces 7 and 9 to their collapsed or folded 45 positions.

End walls comprising relatively spaced boards, planks, or other material, interconnected and braced through suitable means, indicated in their entireties by the numeral 14, are hingedly mounted, as at 15, upon the opposite ends of the bottom section 2 and as will be noted, these end walls may be permitted to be swung upwardly to positions at substantially right angles to the bottom section 2 as is clearly shown in the Figure 1, in the "setting up" of the crate. At this time, the bottom marginal portions of each of the end walls will have abutting 55 engagement with adjacent portions of the bottom section 2 and hence, will be prevented from having further outward pivotal movement with respect to the opposite ends of the crate construction.

45 In order that the upper or free ends of

the end walls 14 will be secured in their upright or relative right angular positions with respect to the crate when in its set up position, spring latch members 16 are provided upon the under sides of the opposite ends of the top section, there being two of such latch members upon each end of the top section 1, such members being secured to adjacent portions of the under sides of the sections, as indicated at 17, while the 70 opposite or free ends thereof are adapted to be spaced downwardly from the top section by reason of the curvature of the latches. Thus, it will be understood that with swinging of the hinged end walls 14 to their upright or right angular position, aforesaid, the free extremities thereof will pass over the spring latch members 16. However, when they have completely passed over and disengaged from the free ends of such members 16, said members will immediately return to their normal positions whereat they will be spaced from the adjacent portions of the under sides of the top section 1, as is shown in the Figure 5, and hence, the downwardly spaced ends of the latch members 16 will abut adjacent portions of the inner sides of the end walls 14 and thereby prevent inward swinging movement of the same.

To permit operation of the latches 16, that is, movement of the same to their inoperative positions whereat they will be disengaged from the adjacent portions of the end walls 14 and such end walls will be permitted to swing inwardly to their folded or collapsed positions on the bottom section 2, latch operating rods 18 are rotatably mounted in suitable bearings 19 upon the upper sides and opposite end portions of the top section 1, the opposite ends of said rods being provided with curved right angularly disposed extensions 19' which, in turn, are slidably engaged through eyelets or similar devices 20 integral with or otherwise secured to the free end portions of the various latch members 16. A right angularly off-set handle 21 is formed in the intermediate portion of each of these several latch rods 18, and obviously, by rocking or pivoting the same, corresponding rocking movement of the arms 19' will be effected and thus, said arms 19' when moved in the proper direction, will exert an upward pull upon the free ends of their respective members 16 for moving such latch members to positions adjacent or approximately flush with the top section 1 and thereby permitting of the free inward swinging movement of the end walls 14 to their folded or collapsed positions, as shown in the Figure 2. Staples, or other suitable keepers, are preferably arranged upon appropriate portions of the top section 1 whereby to permit of engagement of the looped ends of the 130

several pintles 21 thereover whereupon shields, locks, or other devices 22, are passed through the same to prevent fraudulent operation of the latch rods 18, as to enable 5 tampering with the crate, subsequently to movement of the end walls 14 to their upright or right angular positions.

Side walls 23 comprising relatively interconnected and braced boards or planks, or 10 other elements, are provided the crate construction, the same being hinged to the upper marginal portions of the strips 3 secured to the opposite sides of the bottom section 2. By this mounting of the side 15 walls 23 upon the strips 3, it will be understood that the lower portions thereof will be positioned about the hinged mounting of the end walls 14, and at this point, it is to be understood that the height of the strips 20 3 are such as to approximately correspond to the thickness of the end walls 14. Thus, when said end walls 14 are in their folded positions, as shown in the Figure 2, the side walls 23 may be freely swung downwardly 25 and over such end walls, as is shown in the Figure 3, into substantial parallelism with the bottom section 2. Likewise, it is to be noted that the lengths of the several end walls 14 are such as to permit the same to 30 be swung within the side walls 23 when said walls have been moved to their upright or right angular positions, as shown. Thus, following the upward swinging of the walls 23 to their right angular positions, the end 35 walls 14 may be freely swung upwardly to their respective right angular positions, as when upright, will engage the adjacent inner sides of the end portions of the side walls 23 and serve as means for positively 40 retaining the same in their respective upright positions and against undesired swinging or shifting movement to collapsed or folded positions.

In use of my improved crate, to "set up" 45 the same, it is only necessary that the hooks 12 be disengaged from their respective keepers 13 upon the bottom section 2, whereupon the top section is pulled upwardly to that position as shown in the Figure 3. At 50 this time, the hingedly connected brace sections 7 and 9 will be moved into substantial parallel positions as shown in said Figure 3. Following this, the side walls 23 are swung upwardly to their right angular positions, whereupon the several end walls are 55 then swung upwardly to those right angular positions as shown in the Figure 1, thereby locking or bracing the side walls 14 in their upright or right angular positions 60 and preventing the same from having undesirable inward shifting movement to collapsed positions. With swinging movement of the end walls 14 to their upright and right angular positions as shown in the Figure 1, 65 it will be understood that the free ends

thereof will flex the curved free ends or extremities of the latch members 16 to such an extent as to permit of movement of said end walls 14 to their full right angular or upright positions, whereupon the latch members 16 will be disengaged and immediately returned to their locking positions, as indicated in the Figure 5, whereat they will have abutting engagement with adjacent portions of the free ends of the end walls 14 and by consequence, will prevent inward swinging movement of the same. With arrangement of the end walls 14 in their upright positions and locked in such positions 70 through the medium of the latch members 16, the looped ends of the handles of the several latch rods 18 will be engaged over the staples or keepers provided upon corresponding portions of the top section 1 and at this time, shields, locks, or other devices 75 22 may be passed through said keepers over the looped ends of the handle portions 21 and thus, such latch rods 18 will be prevented from being fraudulently operated or tampered with. Should it now be desired to 80 fold the crate, one or both of the latch rods 18 are operated by swinging the respective handles 21 upwardly and outwardly from the top section 1. With such movement, the curved arms 19' will be swung upwardly, 85 thereby flexing the free ends of the curved latch members 16 to such an extent as to permit of free and uninterrupted inward swinging movement of the end walls 14 thereby to closed positions, as shown in the Figure 2. To further fold or collapse the 90 crate, the side walls 23 are now swung downwardly to the positions as shown in the Figure 3, and following this, the hinged connection as between the brace sections 7 and 9 is "broken" and pivotal folding movement is effected as between these brace sections until the same assume positions as 95 shown in the Figure 4, whereat the top and bottom sections 1 and 2 respectively, will be 100 arranged in juxtaposed positions and will completely house and overlie the folded end and side walls 14 and 23 respectively. At this time, the hooks 12 upon the intermediate portions of the guard bars 10 are engaged with their respective keepers 13 and thus, the crate will be securely retained in 105 its folded position.

It will be noted that with arrangement of the crate in folded position that the guard bars 10 will be arranged adjacent the outer sides of the hingedly connected brace sections 7 and 9 and likewise, adjacent the opposite sides of the top and bottom sections 1 and 2. Because of this, relative lateral movement as between said top and bottom sections will be prevented, and similarly, relative vertical movement as between such sections will be obviated. Also, the guards will serve as means for preventing the in- 110 115 120 125 130

terference or undesired engagement of other objects as between the top and bottom sections.

Manifestly, the construction shown is capable of considerable modification, and such modifications as is within the scope of my claims, I consider within the spirit of my invention.

I claim:

10. 1. A foldable crate comprising a top and a bottom, hingedly connected sectional braces pivoted at their opposite ends to the sides of said top and bottom, means on the braces adjacent said points of hinging for limiting pivotal movement of the same in one direction, horizontally swingable side and end walls hinged adjacent the marginal portions of said bottom, manually movable means on the top engageable with said end walls, at times, for holding the same in upright positions, and guards having diagonally disposed opposite extremities fixedly secured to the opposite sides of said top and laterally off-set from the same and 25 from said braces to allow the braces to fold therebetween.
2. A foldable crate comprising a top and a bottom, hingedly connected sectional braces pivoted at their opposite ends to the 30 sides of said top and bottom, means on the braces adjacent said points of hinging for limiting pivotal movement of the same in one direction, horizontally swingable side and end walls hinged in different planes ad-
- 35 jacent the marginal portions of said bottom, curved spring latch members secured to the under side and opposite end portions of said top having the free ends thereof disposed

outwardly and normally spaced downwardly from the adjacent portions of said top, latch rods rotatably mounted upon the upper sides and opposite end portions of said top, curved arms off-set from said latch rods and engaged with the free ends of said latch members for imparting outward movement thereto, the free ends of said latch members being adapted to have abutting engagement with adjacent portions of the free ends of said end walls, at times, guards having diagonally disposed opposite portions fixedly connected to the opposite sides of said top and off-set laterally from said braces and the opposite sides of the bottom, and interengageable means on corresponding portions of the opposite sides of said top and bottom for securing the same in juxtaposed position.

3. A foldable crate comprising a bottom, side and end walls hingedly connected thereto, a top, foldable brace members connecting said bottom and top and adapted to retain the latter in opened or extended position, guard members each comprising a rod having their opposite ends connected to the opposite sides of said top and their medial portions depending thereupon, said guard members being adapted to extend over said bottom when the crate is in folded position to prevent lateral movement of the top and bottom with respect to one another, and means for detachably connecting said guard members to said bottom.

In witness whereof I have hereunto set my hand.

JOHN McGARY ALLEN.
